OVERFLOW FOR LIQUID STORAGE TANKS

Orrin H. Pilkey, Chicago, Ill., assignor to Chicago Bridge & Iron Company, a corporation of Illinois

Application October 11, 1946, Serial No. 702,806

5 Claims. (Cl. 137—21)

1

This invention relates to an overflow, and more particularly to an overflow for a liquid storage tank.

Liquid storage tanks are generally provided with an overflow outlet at the normal high-liquid level of the tank to limit the height of the liquid within the tank. It has been customary in the past to provide such overflow outlets with a Weir box to increase the efficiency of the outlet. Weir boxes generally are expensive to fabricate and their installation is not only difficult but is attended with the danger of ice forming in the liquid retained in the Weir box and the consequent stoppage of the overflow.

I have invented an am herein disclosing and claiming an overflow for a liquid storage tank which is inexpensive to manufacture and possesses no difficulty of installation and is not endangered by ice formation, and which also increases the capacity of the overflow pipe by inhibiting the formation of a vortex and thereby preventing air from being sucked into the overflow and breaking the vacuum.

The invention will be described as embodied in the accompanying drawings, in which

Fig. 1 is a side elevation of a liquid storage tank;

Fig. 2 is a vertical section along lines 2—2 of Fig. 1;

Fig. 3 is a horizontal section of the top of the outlet along lines 3—3 of Fig. 2; and

Fig. 4 is a view, partly in section, of the outlet viewed from the interior of the tank.

Referring more particularly to Fig. 1, I show a spherical liquid storage tank 10 supported by a plurality of posts 11 having vapor vents 12 in its top portion and an overflow pipe 13 extending from near the top of the tank down along its side. The overflow pipe 13 opens to the interior of the tank through an opening 14 and is normally positioned at the nominal high liquid level of the tank. Positioned above the opening is a substantially horizontal plate 15, the plate in the embodiment shown being generally semi-circular in shape, although some departure from semi-circular shape to accommodate the curving side walls of the tank is necessary as is shown in Fig. 3. The horizontal plate 15 is a vortex inhibiting member which, being positioned just above the opening 14, prevents the formation of vortices in the outlet and hence greatly increases the capacity of the overflow pipe. The plate 15 is connected to and may be supported by a vertical plate 16 attached to the side of the tank and bisecting the opening. This vertical plate 16 serves

2

not only partially to support the horizontal plate 15 but also aids in preventing rotation of the liquid entering the outlet pipe. As can be seen, no part of the overflow acts as a container for the liquid within the tank, such as was common in the old style Weir boxes. Free circulation of the liquid adjacent the opening is therefore possible and the danger of the liquid freezing in the outlet in extreme temperatures is greatly lessened.

The shape of the horizontal plate 15 may, of course, be varied. I have found, however, that a shape being substantially a section of a circle as shown is simple and efficient. As an example, 15 for a 3" overflow pipe, that part of the horizontal plate adjacent the shell has a length of 15" and a width from the shell edge to the interior edge of 10". For a 4" overflow pipe the length adjacent the shell is 18" and the width from the shell edge to the interior edge is 12". For a 6" overflow pipe the dimensions are 24" and 18" respectively. The vertical length of the vertical plate is relatively unimportant as long as it has sufficient length to bisect the opening.

20 While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. In a liquid storage tank an overflow comprising: an overflow outlet on the side of the tank opening to the interior thereof at the nominal high liquid level, an outlet pipe on the exterior of the tank terminating flush with the side of the tank and connected to the overflow outlet and a substantially horizontal flat plate attached to the inside of the tank substantially tangent to the upper portion of the overflow outlet.

2. In a liquid storage tank having an outwardly convex sheet metal upper portion, an overflow comprising: an overflow outlet on the upper portion of the tank opening to the interior thereof, an outlet pipe on the exterior of the tank terminating flush with the side of the tank and connected to the overflow outlet at the nominal high liquid level, a substantially horizontal plate mounted on the inside of the tank substantially tangent to the upper portion of the outlet, and a substantially vertical plate within the tank and longer than the diameter of the opening bisecting the outlet.

3. The overflow of claim 2 in which the hori-

horizontal plate is attached to the tank and is substantially semi-circular in shape.

4. The overflow of claim 2 in which the horizontal plate is substantially a section of a circle having a radius of at least three times the diameter of the outlet opening.

5. The overflow of claim 2 in which the horizontal plate is substantially semi-circular in shape and is supported at least in part by the vertical plate.
